(57) **CLAIM**

The ornamental design for a toddler sandal, as shown and described.

DESCRIPTION

FIG. 1 is a front, right, and top perspective view of a toddler sandal, showing my design.

FIG. 2 is a rear, left, and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof; and,

FIG. 8 is a bottom plan view thereof.

A toddler sandal for a left foot is a mirror image of the toddler sandal for a right foot as shown in FIGS. 1 to 8.
